CHOKER SLING

Arthur A. Berndt, Chicago, Ill.

Application November 5, 1945, Serial No. 626,776

15 Claims. (Cl. 294—74)

1

The invention relates to choker slings of the type wherein a choker fixedly connected to an end of a cable has releasable engagement with an intermediate portion of the cable to form a loop therewith. More particularly, the invention relates to an improved choker including matching hooks pivotally supported for movement in opposed relation by a cable or rope anchorage member of special design.

An object of the invention is to provide a choker having separable parts and which may be readily applied to the cable at any point to form a loop of the desired size, and wherein said separable parts comprise overlapping and coacting hooks for engaging the cable in a manner to completely surround the same, thereby eliminating the possibility of inadvertent release of the cable.

A more specific object of the invention is to provide a choker having separable parts in the form of pivoted latching hooks and which function in combination with a pivoted latch for locking the cable to the hooks.

Another object resides in the provision of a choker having a cable anchorage member of special shape and which said member, notwithstanding its shape, may have a dead end connection with the cable in any conventional manner.

Another object is to provide a choker having separable hooks pivoted to a member so that the cable and member may assume a straight line position under load, thereby eliminating any bending of the cable at its dead end connection with the member.

A further object is to provide an improved choker having matching hooks and which overlap and support each other when the hooks are closed on a cable, whereby the stresses applied upon lifting of the load are uniformly distributed to both hooks.

With these and various other objects in view, the invention may consist of certain novel features of construction and operation as will be more fully described and particularly pointed out in the specification, drawings and claims appended hereto.

In the drawings which illustrate an embodiment of the invention, and wherein like reference characters are used to designate like parts—

Figure 1 is an elevational view of one embodiment of the choker of the invention showing the same in operative relation with a cable to form a loop therewith;

Figure 2 is an elevational view of another embodiment showing the pivoted hooks in combina-

2

tion with a latch in an inoperative separated relation;

Figure 3 is a perspective view of the choker showing the hooks in separated relation, similar to Figure 2;

Figure 4 is a perspective view of the choker with the pivoted hooks and latch in closed operative position such as they assume when in engagement with a cable;

Figure 5 is a sectional view taken vertically through the choker of Figure 2 showing the parts in operative relation with a cable;

Figure 6 is an end elevational view illustrating the overlapping relation of the matching hooks when in closed position;

Figure 7 is a sectional view illustrating the construction and coaction of the matching hooks as shown in Figure 6;

Figure 8 is a fragmentary sectional view showing one conventional form of cable connection for the cable anchorage of the choker;

Figure 9 is a fragmentary sectional view showing another conventional form of cable anchorage;

Figure 10 is a fragmentary sectional view showing still another form of cable anchorage;

Figure 11 is a view showing the manner of forming a sling with the present choker to lift a load; and

Figure 12 is another view also illustrating the use of the choker of the invention.

Referring to the drawings, the embodiment selected for illustrating the invention essentially comprises a cable anchorage 10 having a socket connection at one end with a cable 11 and being provided with a yoke 12 at its opposite end, the said yoke forming spaced leg portions 13. As best shown in Figure 5, the cable and anchorage, which for purposes of description will be termed a socket portion, has a dead end connection with cable 11. This dead end connection with the cable may be made according to any of the well known socket connections, the structure selected for disclosure in Figure 5 including the threaded screw 14 having exterior threads 15 adapted to have threaded engagement with the threads 16 formed interiorly of the socket portion 10. Before the parts are assembled the cable 11 is fixedly secured to the screw 14 by the plug 17. The plug preferably has a tapering formation to facilitate its entrance centrally of that part of the cable within screw 14. As tension on cable 11 increases it will be understood that the plug 17 will be drawn into the screw 14 to a greater extent, thus increasing the locking

40
45
50
55

action on the cable. Connection between the screw 14 and the choker is made by threading the socket portion 10 to said screw.

The choker of the invention additionally comprises a pair of matching hooks 18 and 20 having pivotal connection to socket portion 10 through the instrumentality of yoke 12. The pivot pin 21 extends through the legs 13 of the yoke to pivotally secure the hooks 18 and 20 thereto. Said pivot pin 21 is releasably retained in place by cotter pin 22. A latch member 23 may also be pivoted to the socket portion 10, Figure 2, the latch having connection with the pivot pin 21. The latch member is located between the hooks 18 and 20 and said member at its free end pivotally carries a cable engaging shoe 24 pivoted to member 23 centrally at 25. The cable engaging surface of shoe 24 may be roughened by grooves or serrations identified by numeral 26 to increase the holding action of said shoe as regards the cable. The shoe is pivoted to the end of the latch member 23 so as to provide for substantially straight line movement of the shoe in a direction parallel to that of the cable. Accordingly, maximum contact of the shoe with the cable is assured. It will be observed that the free end of latch member 23 is pointed, providing the angular edges 27, which edges function as stop means to limit the extent of pivotal movement of the shoe 24. The said end of latch member 23 may be pointed or rounded for this purpose, and which functions to restrict movement of the shoe to an extent where it will have substantially straight line travel with the cable, with just sufficient pivoting action to securely engage the cable for locking the same to the hooks 18 and 20 when said hooks are in closed position on the cable.

Referring more particularly to said hooks, it will be observed that the same have similar formations at their free ends although the formation on hook 18 is oppositely directed with respect to the formation on hook 20. In accordance with the invention, the hook 18 is provided with a U-shaped hook portion 28 and an overlapping portion 30. Said portion 28, as a result of its curved formation, provides a trough 31 of a size to receive the cable 11. In a similar manner hook 20 is provided with a U-shaped hook portion 32 forming the trough 33 and with an overlapping portion identified by numeral 34. The overlapping portions 30 and 34 of the respective hooks are directed toward each other and when the hooks are in contact with each other the portion 30 has overlapping relation with hook portion 32 and portion 34 has overlapping relation with hook portion 28. This closed position of the hooks with the various portions overlapping is clearly illustrated in Figures 6 and 7.

The purpose of the choker of the invention is to form a sling with cable 11 for lifting purposes. As illustrated in Figures 1 and 5 the cable 11 has connection at its end with the choker through the socket portion 10. The hooks 18 and 20 are caused to engage the cable at some intermediate point on the same, thereby forming a sling or loop of the desired size. With the cable 11 in associated relation with the hooks it will be understood that said cable will be received by the respective hook portions 28 and 32 which provide a groove of a size especially designed to receive said cable. When the hooks are closed to contact each other the hook portions 28 and 32 coact to provide a groove for the entire width of said hooks although as regards each hook, its

respective hook portion extends for approximately one-half of its width, with the other half forming the overlapping portion.

The shoe 24 of the latch 23 is designed so as to have location within the cable receiving grooves when the hook members are in contact. Accordingly, with a cable located in said groove the shoe 24 will be caused to engage the cable, its position depending on pivotal movement of the latch. It is entirely optional as to whether or not the latch is used in connection with the pivoted hooks since the latch has no function in the lifting of the load. The purpose of the latch is to lock the cable to the hooks to prevent spreading or release of a load when the same is deposited on a loading platform or other support. As shown in Figure 5, the latch has a position outside of the loop or sling and the same is moved to an operative position in contact with the cable when the cable is under tension due to the weight of the load. The action of the latch in engaging the cable and locking the same to the hooks is clearly shown in Figure 5. Tension on the cable is released when the load is deposited on the loading platform or other support. However, the latch prevents the sling from expanding, thus holding the load together and preventing spreading of said load. Locking of the cable in this manner is desirable at times in connection with certain loads.

Another feature of the present invention resides in the pivotal connection of the hooks 18 and 20 with the cable anchorage, namely, the socket portion 10. Said pivotal connection enables the socket portion and the cable to assume a straight line position under load, as is evidenced by reference to Figures 11 and 12. Accordingly, all bending of the cable at the connection with the socket portion is eliminated. It will be appreciated that a continued bending of the cable at the connection with the socket portion would very soon cause fatigue of the cable at this point, requiring frequent repairs. By providing a straight line pull all bending of the cable at said connection is eliminated.

The cable anchorage member of the present choker has a special shape particularly adapting it to the lifting of loads, as best shown in Figures 11 and 12. The said cable anchorage or socket portion 10 is substantially cylindrical in shape, having a slight taper from a reduced diameter 35 adjacent yoke 12 to a somewhat enlarged diameter 36 at the end opposite the yoke. This tapering formation is not at all important, but what is important is the curvature or contour of the cable end or nose of the socket portion which is made dome-shaped. The curvature of this domed end of the socket portion substantially comprises a parabola. A parabolic curve has been selected in order to facilitate contact of the dome portion with the load being lifted by the loop or sling. The parabolic curve and cylindrical contour of the anchorage member have coacting functions in the lifting of a load since the curve forms a variable contact portion for engagement with the load, whereas the cylindrical contour of the anchorage member makes it possible for the same to roll on the load and adjust itself in whatever direction the tension may be applied. This is best illustrated in Figures 11 and 12 which show the action of the present choker in forming a sling for lifting a load. When the present device is employed for lifting a large load, indicated by numeral 37, Figure 11, the point of contact 75 of the load with the dome-shaped portion 36 is

well toward the base of the parabolic curve on which this dome-shaped portion is formed. Also it will be noted that the hooks 18 and 20 are almost in a straight line with the axis of the anchorage member. More particularly, the hooks have a slight angular position inwardly toward the load.

Referring to Figure 12, where the device of the invention is shown in lifting relation with a load of relatively small size, it will be observed that the point of contact of the dome-shaped portion 36 with the load is more toward the top of said portion, or, in other words, said point of contact is closer to the nose of the cable anchorage member. Also the hooks are bent at an angle which approximates 90 degrees.

In both instances the cable has a direct line pull with its anchorage member so that bending of the cable at said anchorage is eliminated. Also the action of the cable upon tension being applied to the same is to close the pivoted hooks and to hold them in closed relation in contact with each other. With the hooks so closed the cable is effectively held thereby, since the cable has location in the grooves provided therefor, with the result that a positive act is required in order to release the cable from the hooks after tension has been removed from the cable.

The dead end connection of cable 11 with its anchorage member may take several different forms as previously mentioned in connection with Figure 5. For example, Figure 8 shows a hot socket connection wherein the screw 114 is formed with a tapering central bore 119 having its narrow opening at the head end of the screw and its wide opening at the opposite end. An end of cable 111 is inserted in said tapering bore and the strands are flared and secured to said screw 114 by pouring hot zinc or the like into the wide end of the bore. The connection securely unites the cable to the screw 114 and the same is screwed into socket portion 110 of the choker for anchoring the cable thereto.

In Figure 9 the cable anchorage member 140 is externally grooved, providing a thimble for receiving the cable 111, which is looped around the thimble of the member and securely fastened by means of the crosby clip 141. Figure 10 shows a somewhat similar connection with anchorage member 150 being externally grooved to provide a thimble portion for receiving the loop of the cable 111. In this form of connection, the cable end is spliced to the cable and the splice is taped or bound as at 151.

The invention is not to be limited to or by details of construction of the particular embodiment thereof illustrated in the drawings, as various other forms of the device will of course be apparent to those skilled in the art without departing from the spirit of the invention or the scope of the claims.

What is claimed is:

1. In a device of the character described, in combination, a socket portion having a socket connection with a cable, of a pair of hooks pivoted to the socket portion at the end opposite said cable connection, said hooks having oppositely directed formations so that they overlap and coact when in contact, and a latch member pivoted to the socket portion and having location between the pivoted hooks.

2. In a device of the character described, in combination, a socket portion having a socket connection with a cable, of a pair of hooks pivoted to the socket portion at the end opposite

said cable connection, said hooks having oppositely directed formations so that they overlap and coact when in contact, and a latch member pivoted to the socket portion and located between the pivoted hooks, said latch member including a part having pivotal movement on the same axis as the hooks and a cable engaging part pivoted to the end of said first mentioned part.

3. In a device of the character described, in combination, a socket portion having a dead end connection with a cable, a pair of hooks pivoted to the socket portion at the end opposite said cable connection, said hooks having oppositely directed formations at their free ends and each including a hook portion and an overlapping portion, and a latch member pivoted to the socket portion and having location between the pivoted hooks.

4. In a device of the character described, in combination, a socket portion having a dead end connection with a cable, a pair of hooks pivoted to the socket portion at the end opposite said cable connection, said hooks having oppositely directed formations at their free ends and each including a hook portion and an overlapping portion, and a latch member pivoted to the socket portion on the same axis as said hooks, said latch member having location between the pivoted hooks.

5. In a device of the character described, in combination, a socket portion having a dead end connection with a cable, a pair of hooks pivoted to the socket portion at the end opposite said cable connection, said hooks having oppositely directed formations at their free ends and each including a hook portion and an overlapping portion, and a latch member pivoted to the socket portion and located between the pivoted hooks, said latch member including a part having pivotal movement on the same axis as the hooks and a cable engaging part pivoted to the end of said first mentioned part.

6. In a device of the character described, in combination, a socket portion having a dead end connection with a cable, said socket portion having spaced legs projecting from the end opposite said connection with the cable, a pair of hooks located between and pivoted to the legs, said hooks having oppositely directed formations at their free ends and each including a hook portion and an overlapping portion, and a latch member located between the hooks and also pivoted to said legs on the same axis as the hooks.

7. In a device of the character described, in combination, a socket portion having a dead end connection with a cable, said socket portion having spaced legs projecting from the end opposite said connection with the cable, a pair of hooks located between and pivoted to the legs, said hooks having oppositely directed formations at their free ends and each including a hook portion and an overlapping portion, and a latch member located between the hooks, said latch member including a part pivoted to said legs on the same axis as the hooks, and a cable engaging part pivoted to the end of said first mentioned part.

8. In a device of the character described, in combination, a socket portion having a dead end connection with a cable at one end of said portion, said portion at its other end having an integral yoke providing spaced legs, a pair of cable engaging hooks located between and pivoted to the legs, each said hook having a hook portion and an overlapping portion formed on its free

end, the respective hook portions being overlapped by the overlapping portion of the other hook when said hooks are in contact, and a latch member located between the hooks and also pivoted to said legs on the same axis as the hooks, said latch member including a cable engaging shoe pivoted to the free end of the same.

9. In a device of the character described, in combination, a socket portion having a dead end connection with a cable at one end of said portion, said portion at its other end having an integral yoke providing spaced legs, a pair of cable engaging hooks located between and pivoted to the legs, each said hook having a hook portion and an overlapping portion formed on its free end, the respective hook portions having contact when the hooks are moved toward each other and each hook portion being overlapped by the overlapping portion of the other hook, and a latch member including a part located between the hooks and pivoted to said legs on the same axis as the hooks and a cable engaging shoe pivoted to the free end of said part.

10. A device as defined by claim 6 wherein the pair of hooks and latch member are pivoted to the legs by a pivot pin providing an axis normal to the longitudinal axis of the socket portion, and wherein said socket portion is substantially cylindrical having a tapering formation from a reduced section adjacent the legs to a slightly enlarged section at the cable connection end.

11. A device is defined by claim 8 wherein the pair of hooks and latch member are pivoted to the yoke by a pivot pin providing an axis normal to the socket portion, and wherein said socket portion is substantially cylindrical having a tapering formation from a reduced section adjacent the yoke to a slightly enlarged section at the cable connection end.

12. In a choker, in combination, a member having a dead-end connection with a cable at one end thereof, a pair of hooks pivoted to the member at the other end thereof for movement toward and from each other, said hooks having oppositely directed formations at their free ends

and each including a hook portion and an overlapping portion.

13. In a choker, in combination, a member having a dead-end connection with a cable at one end thereof, said member having spaced legs projecting from the opposite end thereof, a pair of hooks located between and pivoted to the legs for movement toward and from each other, said hooks having oppositely directed formations at their free ends and each including a hook portion and an overlapping portion.

14. In a choker, in combination, an anchorage member having a dead-end connection with a cable at one end thereof, said member at its other end providing an integral yoke forming spaced legs, a pair of cable engaging hooks located between and pivoted to the legs for movement toward and from each other, each said hook at its free end having a hook portion and an overlapping portion formed thereon, the respective hook portions being overlapped by the overlapping portion of the other hook when said hooks are in contact, and said anchorage member being substantially cylindrical and having a dome-shaped portion at the end connecting with said cable.

15. In a choker, in combination, an anchorage member having a dead-end connection with a cable at one end thereof, said member at its other end providing an integral yoke forming spaced legs, a pair of cable engaging hooks located between and pivoted to the legs for movement toward and from each other, the pivot axis of the hooks being disposed normal to the longitudinal axis of the anchorage member, each said hook at its free end having a hook portion and an overlapping portion formed thereon, the respective hook portions having contact when the hooks are moved toward each other and each hook portion being overlapped by the overlapping portion of the other hook, and said anchorage member being substantially cylindrical and having a dome portion of parabolic shape at the end connecting with said cable.

ARTHUR A. BERNDT.
